UNITED STATES PATENT OFFICE.

CHARLES D. MYERS AND CLAUDE D. MYERS, OF NEW YORK, N. Y.

DESIGN FOR WRITING-PAPER.

Specification forming part of Design No. 7,888, dated November 24, 1874; application filed October 23, 1874.
[Term of Patent 3½ years.]

To all whom it may concern:

Be it known that we, CHARLES D. MYERS and CLAUDE D. MYERS, of the city of New York, in the county and State of New York, have jointly invented a new Design for Writing-Paper, of which the following is a specification:

The nature of our design is fully represented in the accompanying drawing, to which reference is made; and consists in a corrugated or embossed surface, composed of reversed diagonal lines raised on the surface of note-paper, each diagonal line of the proper length to represent the space between the ruled lines of ordinary note-paper. The lines in each space being reverse to the one adjoining, it gives a different shade to each space, such shading being caused by the light striking the ribs or raised surfaces of the diagonal lines at different angles. This shading, more especially on tinted paper, gives a beautiful appearance to the surface of the paper, and saves the necessity of ruling.

This style of surface may be made to represent any width of ruling, giving any width of space desired, and may be made on either tinted or white paper.

Having thus described our invention, what we claim as new, and desire to secure by Letters Patent, is—

A design for writing-paper, the surface of which is corrugated or embossed to represent fine diagonal lines, each row representing the space between the lines on ordinary writing-paper, and each row of lines being reverse to the other, so as to cause a different tint to the shading of the space represented by the length of the lines or corrugations, substantially as set forth.

CHARLES D. MYERS.
